J Rabbeth.
Diaper Pin.

No 4938 Patented Jan 21. 1847

UNITED STATES PATENT OFFICE.

JAMES RABBETH, OF MANSFIELD, CONNECTICUT.

DIAPER-PIN.

Specification of Letters Patent No. 4,938, dated January 21, 1847.

To all whom it may concern:

Be it known that I, JAMES RABBETH, of Mansfield, in the county of Tolland and State of Connecticut, have invented a new 5 and Improved Pin for Fastening Persons' Clothing; and I do hereby declare that the following is a full and exact description.

The nature of my invention consists in providing a pin with two tubes (one fastened to the head, and the other to cover the point when used, and removable therefrom at pleasure) which tubes are connected together by means of an elastic band, in such a manner as to hold and keep the pin in its 10 place when worn or used, and to prevent the point of the pin from piercing or otherwise in any manner injuring the person wearing or using the same.

To enable others skilled in the art to make 20 and use my invention, I will proceed to describe its construction and operation.

I make in the first place two tubes of metal of about one fourth of an inch in length with two flat sides, into one of which 25 tubes I insert and firmly secure the head or blunt end of a pin; the other tube is designed to receive and cover the point of the pin when in use, and may be put on to said point and removed therefrom at pleasure.

30 I then provide an elastic band composed of india rubber or other elastic substance or materials, of sufficient length doubled, to connect together the two tubes when attached to the pins, and to hold in its place

the tube designed for the point of the pin 35 when the same is in use. This band I put over the ends and upon the flat sides of the tubes, and then insert each of the tubes with the band so arranged upon the same, into a metal cap so constructed and fitted as to 40 confine the band closely and firmly to the tubes. When the pin is thus completed the two tubes appear to be connected together by two bands fastened to opposite sides of the tubes;—all which is shown by the 45 accompanying drawing.

To fasten the pin into a garment it is only necessary to insert the point of the pin into the movable tube; and to remove it from a garment, it is necessary only to take the 50 movable tube from the point of the pin, which the elasticity of the band connecting the two tubes together will permit to be done with ease and facility.

What I claim as my invention, and what 55 I desire to secure by Letters Patent, is—

The combination of the tubes, caps, elastic bands and pin as hereinbefore described so as to form a pin in such manner as that when used the pin will be confined or held in 60 its place and the point thereof prevented from piercing or otherwise injuring the person wearing or using the same.

Hampton, January 13th, A. D. 1847.

JAMES RABBETH.
